(57) CLAIM

The ornamental design of a removable shoe ornament set, as shown and described.

DESCRIPTION

A sports shoe that's Velcro on the outside and has two sets of patches, which come in a variety of colors and are interchangeable to the shoe. It is intended to wear on your feet, both children sizes as well as adults.

FIG. 1 is an exploded view of a removable shoe ornament set showing my new design.

FIG. 2 is a front elevational view thereof.

FIG. 3 is a rear elevational view thereof.

FIG. 4 is a top plan view thereof.

FIG. 5 is a right side elevational view thereof; and,

FIG. 6 is a left side elevational view thereof.

The shoe shown in broken lines is for illustrative purposes only and forms no part of the claimed design.
